UNITED STATES PATENT OFFICE.

ALBERT DUDLY, OF MENOMINEE, MICHIGAN.

DESIGN FOR A SLIDE-PIECE FOR WRENCHES.

SPECIFICATION forming part of Design No. 34,901, dated August 6, 1901.

Application filed July 1, 1901. Serial No. 66,789. Term of patent 14 years.

To all whom it may concern:

Be it known that I, ALBERT DUDLY, a citizen of the United States, residing at Menominee, in the county of Menominee and State 5 of Michigan, have invented and produced a new and original Design for a Slide-Piece for Wrenches; and I do hereby declare the following to be a full, clear, and exact description of the same, reference being had to the accompanying drawings, forming a part thereof.

Figure 1 of the drawings represents a side elevation, Fig. 2 a front elevation, Fig. 3 an upper end view, and Fig. 4 a lower end view, of a slide-piece of a wrench, the same embodying my new design.

My invention relates to a new and original shape or configuration of the slide-piece of a wrench, the leading or essential feature consisting in the unitary design for the article 20 made subject of illustration and comprising the piece A, having the rectangular vertical passage b, the upper inclination c, and horizontal face d, the planes of which intersect between the short boundaries of said passage, 25 the dovetail projection e, of less width than

the remainder of said slide-piece, surmounting the inclination of same, between the lower extremity of said inclination and aforesaid passage, this projection being provided with a bore f, extending from said lower extremity 30 thereof approximately one-half of its length, and an upper slot g, intersecting the bore, the rounded partly-curved partly-straight short lengthwise edge h, the angular recess i, interrupting the continuity of said edge and 35 open to the passage b, the horizontal lower face j, having round aperture j', the rounded ogee k of the long lengthwise edge, and the flat vertical face m of said long edge.

Having thus described my invention, what 40 I claim as new, and desire to secure by Letters Patent, is—

The design for a slide-piece of a wrench substantially as herein shown and described.

In testimony whereof I affix my signature 45 in presence of two witnesses.

ALBERT DUDLY.
